The ornamental design for a golf club head as shown and described.

DESCRIPTIONFIG. 1 is a top perspective view of a golf club head;
FIG. 2 is a bottom perspective view of the golf club head of FIG. 1;

FIG. 3 is a toe perspective view of the golf club head of FIG. 1;

FIG. 4 is a top view of the golf club head of FIG. 1;

FIG. 5 is a bottom view of the golf club head of FIG. 1;

FIG. 6 is a front view of the golf club head of FIG. 1;

FIG. 7 is a rear view of the golf club head of FIG. 1;

FIG. 8 is a heel side view of the golf club head of FIG. 1; and,

FIG. 9 is a toe side view of the golf club head of FIG. 1. The broken lines shown on the drawings form no part of the claimed design.
